Patented Oct. 29, 1918.

UNITED STATES PATENT OFFICE.

JOHN MILLER, JR., OF AMESBURY, MASSACHUSETTS, ASSIGNOR TO LEWIS H. SHIPMAN,
OF BOSTON, MASSACHUSETTS.

TROLLEY HARP AND SHOE.

1,283,418.

Specification of Letters Patent.

Patented Oct. 29, 1918.

Application filed August 14, 1916. Serial No. 114,689.

To all whom it may concern:

Be it known that I, JOHN MILLER, JR., a citizen of the United States, and a resident of Amesbury, Mass., have invented an Improvement in Trolley Harps and Shoes, of which the following description in connection with the accompanying drawings, is a specification, like letters on the drawings representing like parts.

10 My present invention is an improved trolley-shoe invention for use in transmitting electrical power from a trolley wire to a car or vehicle carrying the harp. In order to overcome many of the difficulties incident to using a rotary trolley wheel, which rapidly wear out bearings, give poor conductivity and are otherwise objectionable;—several types of sliding shoes having been devised. It is an important object of my present invention to improve and perfect the sliding shoe type of trolley harp.

It is also an object of the invention to provide a shoe so balanced and supported and held in contact with the wire, that it will back up readily and without danger of leaving the wire, and being equally efficient in forward or rearward travel. This feature of my trolley shoe being capable of traveling forwardly or backwardly without danger of jumping off the wire, is also an advantage incident to a sliding shoe as distinguished from a freely rotating wheel. In carrying out the invention I have devised a very simple construction, economical to build and apply, and capable of long use and wearability, while affording the important advantages of yielding self-seating contact between shoe and wire, and furthermore, my improved construction insures the holding

40 of the shoe relatively with the wire, on a long bearing, to obtain the benefits of increased conductivity, thus affording one of the most important advantages of a sliding shoe construction as distinguished from a 45 rotary wheel. My sliding shoe with its long wire-engaging groove giving perfect electrical conductivity between the wire and groove without material loss and having a pivoted bearing which only rocks or oscillates 50 slightly, makes possible a construction which will greatly increase the life of the shoe, whereas in rotary trolley wheels but a single point from wheel to wire was employed for conductivity and the rapid rotation of the 55 wheel under the heavy tension of the spring-

pressed pole, constantly wore out the wheel axle bearing with great rapidity.

Referring to the drawings illustrating the preferred embodiments:

Figure 1 is a side view of one form of my improved harp and shoe;

Fig. 2 is a vertical cross sectional view on line 2—2 of Fig. 1.

Fig. 3 is a modified form of trolley shoe and harp and Fig. 4 is a cross sectional view on the line 4—4 of Fig. 3.

I have illustrated a fragmentary portion 1, of a trolley head which is adapted to fit upon the end of a trolley pole (not shown), said trolley head carrying side arms 2 and 3 which constitute a part of the harp. The ends of the side arms 2 and 3 are preferably enlarged as shown at 4 and 5 respectively, Fig. 2, where the ends are bored to receive the axle or pin 6 on which the trolley shoe is supported and which may have a rotative or partially rotative action. To hold the pin 6 in place, I prefer to cut away portions of the ends 4 and 5, as shown at 7 and 8 so that the cotter pin or like 9 may be fitted through appropriate recesses 10 in the ends of the axle 6, and thus hold the same in position.

Mounted upon the axle 6 is a trolley shoe 12 having a peripheral groove 13 therein of suitable form and size to fit upon the trolley wire with which the shoe is to be used. This shoe 12 is preferably oblong in shape so that a relatively long straight portion of the groove 13 may fit and slide upon the wire when the apparatus is in use. As shown in the drawings, this long straight portion of the trolley shoe extends for a considerable length from 14 to 15, lengthwise of the shoe. One portion of shoe 12 is of greater weight than the other, being for example, made solid or the pivot may be eccentric and thus have one portion of greater weight than that on the other side of the pivot as indicated at 17, Fig. 2, constituting a counterweight and tends to hold the shoe 12 in a vertical position when said shoe is free of contact with the trolley wire. However, when the shoe is allowed to contact with the wire and especially during the forward movement of the car carrying the harp 1, the shoe 12 is automatically oscillated upon its axle 6, and the long bearing surface from 14 to 15 of the groove 13 at once is seated upon the trolley wire and the shoe assumes a substan-

2

tially horizontal position, as indicated in the dotted lines of Fig. 1, when in contact with the trolley wire, represented by dotted line A—B. When the shoe first strikes the wire, as the trolley head and pole are positioned for this purpose, the shoe normally has the long portion of its wire-engaging groove standing substantially perpendicular to the wire, owing to the relative position 10 of the pivot and weight of the shoe. With the shoe in such position and with the end portion of the shoe thus first brought into contact with the wire, the instant that the car, pole, and shoe move forward or backward, frictional action between the shoe and wire will cause the shoe to turn upon its pivot, until it assumes its desired position for service with the straight portion of the groove seated upon the wire. Weight 17 will 20 automatically aid in maintaining the long bearing surface contact with the wire and also tend to prevent the rotation of the shoe 12. If, however, the shoe should strike an obstruction, as at switches, guy wires or the 25 like, the shoe can yield and may even be rotated on the axle 6 without injury or damage, and will always tend to be seated on a long bearing contact surface, from 14 to 15 irrespective of which side of the shoe may 30 be the uppermost, and irrespective of the direction of travel, either forwardly or backwardly. This feature is of special importance as means to maintain the long bearing contact surface between the shoe and wire 35 and also maintains a smooth sliding bearing surface while greatly increasing the electrical conductivity of the apparatus. Any suitable metal may be employed for the shoe 12 as well as for the axle 6 and harp 1, 40 the power being transmitted directly from the shoe through the bearing of axle 6 to the harp 1 or by means of bonds or brushes leading from the shoe to the harp. In order to support the peripheral portion of shoe 12 45 upon the axle 6, any construction may be utilized, that shown being a preferred form merely. In the drawings is shown a hub comprising two members 18 and 19 each adapted to slidably fit on axle 6 and to 50 clamp on the central flange 20 of the shoe 12, between the upstanding portions 21 and 22 of hubs 18 and 19, a bolt 23 being threaded through suitable apertures in 20 and 22 and into a tapped recess in the flange 21. I prefer to form flange 20 with a sufficient central 55 recess therein to receive and rest upon hubs 18 and 19. In assembling the shoe, hub 18 is first fitted upon axle 6, then the shoe 12 applied and the central recess in flange 20, 60 fitted over the protecting portion 24 of hub 18, when the second hub 19 is applied and the bolt 23 fitted through the recesses in the respective members and tightened up, thus firmly holding the hub and shoe in an assembled position. The simplicity of this 65 construction

furthermore admits of quick renewal of either of the hub portions, 18 or 19 and the shoe portion 12 should any part become worn, damaged or broken. This feature is of great importance from a practical 70 standpoint.

In the modified form illustrated in Figs. 3 and 4, I have shown a different form of shoe but mounted in the same manner as that just described, excepting that a stop is 75 added to prevent the shoe from complete rotation. In this form of invention, shoe 25 has a counterweight 26 in its lower portion, tending to normally maintain the shoe in Fig. 3 with the straight part 27, of the wire 80 receiving groove 28 in a substantially vertical position. Contact with the trolley wire and particularly the forward movement of the car at once swings the shoe 25 into position for the straight portion 27 of the groove 85 to slide upon the wire, weight 26 aiding in this yielding self-seating action. In order to prevent a complete rotation of this type of trolley shoe, I prefer to affix on axle 6 a short stud, 29, which may be housed within 90 recess 30 in hub 21, the length of said recess 30 determining the limit of the oscillatory movement of the shoe 25 and its hub on axle 6. This form of invention is still 95 more simple and economical than shoe 12 shown in Figs. 1 and 2, and is lighter in weight. Furthermore, one shoe can be substituted for the other, if desired, and by having the pin or stud 29 removable no further change of parts is necessary for 100 this interchangeability.

By the simple and efficient construction of both forms, I am able to employ the best suited material for each part,—thus I may use any composition for the shoe, chilled or malleable iron for the harp, steel for the axle and any appropriate metal for the hub which constitutes the combined hub and bearing. Where any one of the metals is a relatively poor conductor I may apply a suitable brush 110 and bond and preferably arrange a yielding bond of good conducting and spring metal. To this end I provide a bond member comprising spring fork and arms 33, to clasp the hub 19 and connected to the harp at 34 by a conductor, 35, of copper or the like. I also may prefer to apply spring 36, attached at one end to a lug, 37, on the hub, 18, and at the other end to a pin 38 on the harp 1. This aids in giving a yielding limit to the 115 rocking or oscillation of the shoe. The long contact surface of the shoe, and the flexibility of its oscillatory movement on the axle and besides the increased steadyng contact with the wire through said long bearing, largely prevents any jumping of the shoe from the wire, and furthermore, enables the shoe to maintain its proper contact, either 120 when going ahead or backing up. The arrangement of the axle and shoe with the 125

overbalancing weight of the latter, either with or without the addition of the spring 36, also provides a sufficient yielding means to cause the shoe to quickly recover its position when displaced, and to assume its proper seat on the wire without undue strain.

Having described my invention, what I claim as new and desire to secure by Letters Patent, is:

- 10 1. A trolley shoe of the kind described, comprising a trolley harp, a sliding shoe carried by said harp having a relatively long straight wire-engaging grooved portion, and a pivotal connection between the shoe and the harp, so constructed and arranged as to provide an overbalancing weight in the shoe relatively with the pivot, to normally hold the contact portion of the shoe in vertical position, while permitting automatic seating of the shoe on the wire in contact with said straight grooved portion.
- 15 2. A device of the kind described, comprising a trolley harp, a sliding shoe carried by said harp and mounted thereon for partial rotative movement, said shoe having a counterbalancing weight on one side of its mounting to tend to cause said shoe to oscillate thereon, and current carrying means from the shoe to the pole.
- 20 3. A device of the kind described, comprising a trolley harp, a sliding shoe fitted to said harp, said shoe having a relatively long groove with a straight, wire-engaging portion therein, a counterbalancing weight on said shoe at one side of said pivot, a hub portion supporting the shoe on its pivot, current carrying means from said hub to the trolley harp independent of said pivot, and means to limit the relative pivotal movement
- 25 4. A sliding trolley shoe of the kind described, comprising a forked harp member, an axle carried thereby, a pair of co-operating hubs on said axle having extending flange portions intermediate the length of each of said hubs, a trolley shoe adapted to fit over the hub portions between said extending flanges and a bolt extending through said flanges and a portion of the trolley shoe
- 30 5. A sliding trolley shoe of the kind described, comprising a harp having forked arms, an axle carried by said arms, two hub members adapted to be carried by said axle and to support a removable trolley shoe thereon, a trolley shoe adapted to be fitted onto said hub, having a relatively long wire-engaging groove formed therein, the mounting of said shoe relatively with the axle being arranged for a counterbalancing weight to cause the shoe when not in motion to normally be held on said axle with the
- 35 6. A trolley shoe of the kind described, comprising a trolley harp, a sliding shoe carried by said harp, and having a relatively long straight wire-engaging grooved portion, a pivotal connection between the shoe and the harp, so constructed and arranged as to provide an overbalancing weight in the shoe relatively with the pivot to normally hold the contact portion of the shoe in vertical position, while permitting automatic seating of the shoe on the wire in contact with said straight grooved portion, in combination with current conducting means from the shoe to the harp.
- 40 7. A sliding contact trolley shoe of the kind described, comprising a trolley harp, a rotatable mounting for the shoe in the harp, said shoe being unevenly weighted relatively to said mounting in such manner that the friction of the shoe when in motion upon the trolley wire tends to lift the overweighted portion of the shoe whereby a portion of the contact surface is pressed more firmly against the wire.
- 45 8. A sliding contact trolley shoe of the kind described, comprising a trolley harp, a rotatable mounting for the shoe in the harp, said shoe being unevenly weighted relatively to said mounting in such a manner that the friction of the shoe when in motion either forwardly or backwardly upon the trolley wire tends to lift the overweighted portion of the shoe whereby a portion of the contact surface is pressed more firmly against the wire.
- 50 9. A sliding contact trolley shoe substantially elliptical in shape having wire-engaging surfaces on the flatter sides of the ellipse, a trolley harp, and a rotatable mounting for the shoe in said harp so as to permit either of such surfaces to be brought into operative contact with the trolley wire.
- 55 10. A sliding contact trolley shoe substantially elliptical in shape, a trolley harp, a rotatable mounting for the shoe in said harp, operative wire-engaging surfaces on the flatter sides of the ellipse, and a wire-engaging surface substantially in the shape of an arc connecting said operative surfaces, whereby said shoe can be partially revolved on its mounting without becoming disengaged from the trolley wire, the operative sliding contact automatically changing from one of the flat sides of the ellipse to the other flat side.
- 60 11. The combination of a trolley harp, a sliding contact trolley shoe having substantially flat sides with wire-engaging surfaces in each side, and a groove normally in contact with the trolley wire, and connecting the wire engaging surfaces in the sides, said shoe being detachably and rotatably mounted in said trolley harp so that the respective posi-
- 65 12. A trolley shoe of the kind described, comprising a trolley harp, a sliding shoe carried by said harp, and having a relatively long straight wire-engaging grooved portion, a pivotal connection between the shoe and the harp, so constructed and arranged as to provide an overbalancing weight in the shoe relatively with the pivot to normally hold the contact portion of the shoe in vertical position, while permitting automatic seating of the shoe on the wire in contact with said straight grooved portion, in combination with current conducting means from the shoe to the harp.

in vertical position, and means to hold said shoe rigidly on said hub.

6. A trolley shoe of the kind described, comprising a trolley harp, a sliding shoe carried by said harp, and having a relatively long straight wire-engaging grooved portion, a pivotal connection between the shoe and the harp, so constructed and arranged as to provide an overbalancing weight in the shoe relatively with the pivot to normally hold the contact portion of the shoe in vertical position, while permitting automatic seating of the shoe on the wire in contact with said straight grooved portion, in combination with current conducting means from the shoe to the harp.

7. A sliding contact trolley shoe of the kind described, comprising a trolley harp, a rotatable mounting for the shoe in the harp, said shoe being unevenly weighted relatively to said mounting in such manner that the friction of the shoe when in motion upon the trolley wire tends to lift the overweighted portion of the shoe whereby a portion of the contact surface is pressed more firmly against the wire.

8. A sliding contact trolley shoe of the kind described, comprising a trolley harp, a rotatable mounting for the shoe in the harp, said shoe being unevenly weighted relatively to said mounting in such a manner that the friction of the shoe when in motion either forwardly or backwardly upon the trolley wire tends to lift the overweighted portion of the shoe whereby a portion of the contact surface is pressed more firmly against the wire.

9. A sliding contact trolley shoe substantially elliptical in shape having wire-engaging surfaces on the flatter sides of the ellipse, a trolley harp, and a rotatable mounting for the shoe in said harp so as to permit either of such surfaces to be brought into operative contact with the trolley wire.

10. A sliding contact trolley shoe substantially elliptical in shape, a trolley harp, a rotatable mounting for the shoe in said harp, operative wire-engaging surfaces on the flatter sides of the ellipse, and a wire-engaging surface substantially in the shape of an arc connecting said operative surfaces, whereby said shoe can be partially revolved on its mounting without becoming disengaged from the trolley wire, the operative sliding contact automatically changing from one of the flat sides of the ellipse to the other flat side.

11. The combination of a trolley harp, a sliding contact trolley shoe having substantially flat sides with wire-engaging surfaces in each side, and a groove normally in contact with the trolley wire, and connecting the wire engaging surfaces in the sides, said shoe being detachably and rotatably mounted in said trolley harp so that the respective posi-

- 1
tions of its two flat sides can be reversed, thereby bringing a different wire-engaging surface into operative contact with the trolley wire.
- 5 12. The combination of a trolley harp, a sliding contact trolley shoe having substantially flat sides with a wire-engaging surface in each side, and a groove normally in contact with the trolley wire and connecting the 10 wire engaging surface in each side, said shoe being detachably and rotatably mounted in said trolley harp so that the respective positions of its two flat sides can be automatically reversed, thereby bringing opposite 15 wire-engaging surfaces into operative contact with the trolley wire, when the direction of movement of the harp is reversed.
13. The combination of a trolley harp, a sliding contact trolley shoe substantially 20 elliptical in shape and having a continuous wire-engaging surface on its periphery extending around the two flatter sides of the
- ellipse and one of its arc-shaped ends, whereby contact with the trolley wire may be changed from one of the flat contact surfaces to other without having the shoe lose its contact with the wire. 25
14. A sliding contact trolley shoe having two wire-engaging surfaces on its periphery substantially opposite each other and means whereby one of such surfaces is automatically brought into operative position upon the trolley wire when the trolley car moves in one direction and the opposite of such surfaces is automatically brought into operative 30 contact with the wire when such car moves in the reverse direction. 35
- In testimony whereof, I have signed my name to this specification, in the presence of two subscribing witnesses.
